UNITED STATES PATENT OFFICE.

HENRY S. MILLER, OF PHILADELPHIA, PENNSYLVANIA, ASSIGNOR TO HIMSELF
AND SAMUEL H. DAVIS, JR., OF SAME PLACE.

DESIGN FOR SAW.

Specification forming part of Design No. 5,226, dated August 22, 1871.

To all whom it may concern:

Be it known that I, HENRY S. MILLER, of the city and county of Philadelphia and State of Pennsylvania, have invented a new and useful Design for Saw; and I do hereby declare the following to be a clear and exact description thereof, reference being had to the accompanying drawings, which represent a section or portion of the saw and illustrate my invention.

What I claim as new, and desire to secure by Letters Patent, is—

The design for saw, as herein represented and described.

The above signed by me this 15th day of July, 1871.
